UNITED STATES PATENT OFFICE.

CHARLES B. ROSE, OF MCCLINE, ILLINOIS, ASSIGNOR TO VELIE MOTOR VEHICLE COMPANY, OF MOLINE, ILLINOIS, A CORPORATION OF ILLINOIS.

MAGNETO ADJUSTMENT.

1,132,733.

Specification of Letters Patent.

Patented Mar. 23, 1915.

Application filed September 3, 1912. Serial No. 718,359.

To all whom it may concern:

Be it known that I, CHARLES B. ROSE, a citizen of the United States, residing at Moline, in the county of Rock Island and State of Illinois, have invented certain new and useful Improvements in Magneto Adjustment, of which the following is a specification, reference being had therein to the accompanying drawing.

10 My invention relates to engines in which the motive power is supplied by an explosive element ignited by an electric discharge, and it relates more particularly to an adjustment of certain parts simultaneously to 15 serve their continuous alinement as will be hereinafter more clearly set forth.

Referring to the drawings in which similar letters indicate identical parts,—Figure 1 is an end elevation of an explosive engine 20 embodying my invention and part broken away. Fig. 2 is a detail side elevation in part section illustrating my device. Figs. 3 and 4 are details.

In the drawings 1 is an engine of a well 25 known type, and includes the casing 2, which is considered as part of the engine frame, and a casing 3 secured to the casing 2 in any suitable manner, the latter casing being employed to cover mechanism through 30 which the fan and magneto are operated. I show only the sprocket 5 which is rigidly mounted on the crank-shaft 4 of the engine 1. Engaging with the sprocket 5 is a chain 6 which imparts motion to a sprocket 7 rigidly secured on the end of a shaft 8.

The casing 3 is constructed with an opening 9 which registers with a similar opening 10 in the casing 2; through this open space the shaft 8 operates and is journaled in an 40 eccentric sleeve 11 which is turnable in a bearing 12 in the casing 2, the bearing 12 being partly split so that the eccentric sleeve 11 can be held rigidly therein by means of a bolt 13 connecting the split portions of the bearing; the rear end 14 of the sleeve 11 is concentric with the shaft 8, and is journaled in a bearing 15 on a bracket 16 and preferably integral therewith. The bracket 16 is supported on the casing 2 by bolts 17 and 18 fitted to holes in the bracket, but extending through holes in the casing 2 which are of greater diameter than the bolts.

Upon the rear of the bracket 16 is secured a magneto 19, the shaft 20 of which is connected to the shaft 8 by a well known form 55 of coupling 21.

Heretofore when the chain 6 has become slack and it has been necessary to tighten it, the magneto shaft 20 would be disconnected from the shaft 8 and both would have to be 60 adjusted separately, by my improvement however, the adjustment of both shafts is simultaneous and their alinement is maintained, and I secure this by the following simple operation. It is supposed that the 65 chain 6 has become slack, or is too tight, and it is desired to readjust it, the bolt 13 in the bearing 12, and the bolts 17 and 18 which secure the brackets 16 to the casing 2, are first loosened, the eccentric sleeve 11 70 is then turned in the proper direction, and as the shaft 8 is moved thereby, it carries with it the magneto 19 and bracket 16, the latter being supported by the bearing 15 in which is journaled, concentric with the 75 shaft 8, the rear end of the eccentric sleeve 11, the bracket 16 being free to move as the holes in the casing 2 are of greater diameter than the bolts 17 and 18 which operate there-through. As soon as the chain has 80 been adjusted as desired, the bolts are tightened and the parts are held securely in position, the perfect alinement of the shafts 8 and 20 being preserved by reason of the simultaneous movement of the connected 85 parts.

What I claim is—

1. In an engine of the class described having a crank-shaft and an adjustable magneto, the combination with the magneto-shaft, of means to convey power from the crank-shaft to the magneto-shaft to operate the latter, said means including a shaft connected to the magneto-shaft and in alinement therewith, and means to adjust said 95 shaft and magneto-shaft simultaneously to preserve said alinement.

2. In an engine of the class described having a crank-shaft and a magneto adjustably secured to the machine frame, the combination with the magneto-shaft, of means to convey power from the crank-shaft to the magneto-shaft to operate the latter including a shaft connected to the magneto-shaft 100

and in alinement therewith, and means eccentric to the axis of both shafts to adjust them simultaneously.

3. In an engine of the class described, the combination of a frame, a crank-shaft journaled thereon, a sprocket on the crank-shaft, a bracket adjustably mounted on the frame, a magneto supported on said bracket, a magneto-shaft, a shaft connected with the magneto-shaft in alinement therewith and having a sprocket connected by a chain with the sprocket on the crank-shaft to convey power from the latter to operate the magneto, and a sleeve in a bearing on the frame and in which the shaft connected with the magneto-shaft is eccentrically journaled, said sleeve adapted to be turned to vary the tension of the chain and to adjust the bracket and magneto simultaneously.
4. In an engine of the class described, the combination of a frame, and a magneto adjustably mounted thereon, a crank-shaft, a magneto-shaft, and means to convey power from the crank-shaft to the magneto-shaft to operate the latter including a shaft connected to the magneto-shaft and in alinement therewith, and having a sprocket connected by a chain with the sprocket on the crank-shaft to convey power from the latter to operate the magneto, a sleeve in a bearing on the frame and in which the shaft connected with the magneto-shaft is eccentrically journaled, an end of said sleeve concentric with said shaft and movable in a bearing on the bracket, said sleeve adapted to be turned to vary the tension of the chain and to adjust the bracket and magneto simultaneously.

5. In an engine of the class described, the combination of a frame, a crank-shaft journaled thereon, a sprocket on the crank-shaft, a bracket adjustably mounted on the frame, a magneto supported by said bracket, a magneto-shaft, a shaft connected with the magneto-shaft in alinement therewith and having a sprocket connected by a chain with the sprocket in the crank-shaft to convey power from the latter to operate the magneto, a sleeve in a bearing on the frame and in which the shaft connected with the magneto shaft is eccentrically journaled, an end of said sleeve being concentric with said shaft and held in a bearing on the bracket, said sleeve adapted to be turned to vary the tension of the chain and to adjust the bracket and magneto simultaneously.

6. In combination with the driving shaft of the engine, a second shaft, connections between said shafts for imparting motion from the former to the latter, an adjustable magneto having its shaft arranged in alinement with said second shaft, means for adjusting said second shaft and simultaneously adjusting said magneto bodily with its shaft to take up slack in or tighten said

driving connections, together with means for maintaining the magneto-shaft in alinement with said second shaft and securing the magneto in adjusted position.

7. In combination with the engine driving shaft and a counter-shaft each having a spur-wheel thereon, a chain connecting said spur-wheels, a magneto having its shaft arranged in alinement with said counter-shaft, means for adjusting said counter-shaft and said magneto-shaft simultaneously, said means serving to take up slack in said chain, and means whereby the magneto-shaft is maintained in alinement with said counter-shaft and the magneto adjusted in unison therewith without separately adjusting or changing the position of the magneto-shaft relatively to the counter-shaft.

8. In combination with the crank-shaft of the engine, a counter-shaft and means for imparting motion thereto from said crank-shaft, a magneto having its shaft arranged in alinement with said counter-shaft, an eccentric sleeve for adjusting said counter-shaft and taking up slack in said driving means; said sleeve having said counter-shaft journaled therein and itself fitted in a bearing on the machine frame so as to adapt it to be turned to take up slack, and means for maintaining the magneto-shaft in alinement with said counter-shaft and to compel them to move in unison, together with means for adjusting said magneto simultaneously with its shaft and securing it in adjusted position.

9. In combination with the engine crank-shaft, a counter-shaft, connections between said shafts for imparting motion from the former to the latter, an eccentric sleeve in which said counter-shaft is journaled; said sleeve being fitted in a bearing in the machine frame whereby it may be turned and secured in different positions for tightening or loosening said driving connections, a magneto having its shaft coupled to said counter-shaft in alinement therewith, a support for said magneto, means carried by said support for maintaining said magneto-shaft in alinement with said counter-shaft, together with means for adjusting said magneto simultaneously with its shaft and securing it in adjusted position.

10. In a machine of the character described, the combination with a driven shaft, of an eccentric sleeve in which said driven shaft is journaled; said sleeve being fitted in a bearing in the machine frame whereby it is adapted to be turned and secured in different positions for tightening or loosening the driving connections, a magneto having its shaft coupled to said driven shaft in alinement therewith, and a support for said magneto adjustably secured to the machine frame; said sleeve having an end portion concentric with said driven shaft and said

end portion having a bearing in an arm extending from said support, together with means whereby said magneto and its shaft may be adjusted simultaneously with said 5 driven shaft and secured in adjusted position.

In testimony whereof I affix my signature, in presence of two witnesses.

CHARLES B. ROSE.
